CLAIM

The ornamental design for a frozen confection, as shown and described.

DESCRIPTION

FIG. 1 is a perspective view of a frozen confection showing a first embodiment of our new design;

FIG. 2 is a front elevational view thereof, the rear elevational view being a mirror image thereof;

FIG. 3 is a right-side elevational view thereof;

FIG. 4 is a top plan view thereof;

FIG. 5 is a bottom plan view thereof;

FIG. 6 is a left-side elevational view thereof;

FIG. 7 is a perspective view of a second embodiment of a frozen confection showing our new design;

FIG. 8 is a front elevational view thereof;

FIG. 9 is a right-side elevational view thereof;

FIG. 10 is a top plan view thereof;

FIG. 11 is a bottom plan view thereof;

FIG. 12 is a left-side elevational view thereof; and,

FIG. 13 is a rear elevational view thereof.
